[57] **CLAIM**

The ornamental design for a rifle holder, as shown and described.

DESCRIPTION

FIG. 1 is an environmental perspective view of a rifle holder showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof; and,

FIG. 6 is a bottom view thereof.

The broken line showing of the rifle in FIG. 1 and the wingnut and base in FIG. 4 is for illustrative purposes only, and forms no part of the claimed design.
